UNITED STATES PATENT OFFICE.

LEONARD D. TUCKER AND CLARENCE A. BOYLAN, OF KNOXVILLE, IOWA.

CARD HOLDER FOR AUTOMOBILES.

Application filed May 8, 1928. Serial No. 276,129.

This invention relates to card holders for automobiles and more particularly to a device for holding memorandum or license cards in position upon the instrument board 5 of an automobile.

An important object of the invention is to provide a device of this character in which the support may be readily attached to the instrument board without the formation of an 10 opening in the board and may, at the same time, be held in such manner that it will not be displaced by vibration of the vehicle.

A still further object of the invention is to provide a device of this character which 15 will be readily and cheaply constructed and which will be durable and efficient in service.

These and other objects we attain by the construction shown in the accompanying drawing, wherein for the purpose of illustration is shown a preferred embodiment of 20 our invention and wherein:—

Figure 1 is a front elevation showing a holder constructed in accordance with our invention applied to the instrument board of 25 a vehicle;

Figure 2 is a vertical sectional view through the card applied to the instrument board;

Figure 3 is a plan of the blank from which the card holder is produced.

Referring now more particularly to the drawing, the numeral 10 generally designates a metallic plate which is provided at its side and bottom edges 11 and 12 with tabs or flanges 13 which confront the face of the 30 plate in spaced relation thereto and cooperate therewith to receive and hold the edges of a card C. The upper edge of the plate is preferably notched, as at 14, so that the upper edge of the card may be readily grasped 35 to withdraw the same. The bottom edge of the plate has projecting therefrom, at substantially right angles thereto, a tongue 15, the rear end of which is bent forwardly, as indicated at 16, and provided with a terminal 40 portion 17, which normally tends to engage the rear face of the plate immediately above the lower edge thereof. The tongue 15 is formed of spring metal and should be so bent 45 that its engagement with the back face of the plate is fairly forcible.

As is well known to those familiar with the art, the instrument boards 18 of vehicles are usually constructed of metal and in order to stiffen the same are provided at their lower 50 edges with a flange 19 which extends to the rear of the instrument board.

In applying the device to the instrument board, the rear face of the plate is placed against the front face of the board and the spring tongue passed about the flange 19 60 of the board so that its extremities 17 may engage against the rear face thereof. This extremity by its engagement with the flange 19 will prevent downward displacement of the plate 10, and since it resiliently engages 65 the board, will prevent any rattling or any unpleasant noises. In Figure 3 I have illustrated how this device may be conveniently produced by stamping. It will be noted from an inspection of this figure that the tongue 70 15 is formed as a continuation of the plate 10.

Since a device of this character may be applied to the instrument board and may be accordingly arranged in juxtaposition to the speedometer, it may be very conveniently 75 employed for the reception of memoranda cards correlated with the speedometer as, for example, cards indicating the mileage at which the oil of the engine should be changed or other operations upon the vehicle should 80 be performed.

Since the construction hereinbefore set forth is capable of a certain range of change and modification without materially departing from the spirit of the invention, we do 85 not limit ourselves to such specific structure except as hereinafter claimed.

We claim:—

1. A memoranda card holder comprising a metallic plate and a resilient tongue extending from one edge thereof at right angles to the plate and then reverted and brought, at its free end, yieldingly into contact with the plate adjacent said edge. 90

2. A memoranda card holder comprising a metallic plate and a resilient tongue extending from one edge thereof at right angles to the plate and then reverted and brought, at its free end, yieldingly into contact with the plate adjacent said edge, the terminal of said 100 reverted portion being downturned and flatly confronting the rear face of the card holder.

3. A memoranda card holder comprising a metallic plate and a resilient tongue extending from one edge thereof at right angles to the plate and then reverted and brought, at its free end, yieldingly into contact with the plate adjacent said edge, the plate having 105 means at its edges for engaging the edges of a card, the tongue comprising an integral extension of said plate. 110

4. A memoranda card holder comprising a metallic plate and a resilient tongue extending from one edge thereof at right angles to the plate and then reverted and brought, at its free end, yieldingly into contact with the plate adjacent said edge, the terminal of said reverted portion being downturned and flatly confronting the rear face of the card hold-

er, the plate having means at its edges for engaging the edges of a card, the tongue comprising an integral extension of said plate. ¹⁰

In testimony whereof we hereunto affix our signatures.

LEONARD D. TUCKER.
CLARENCE A. BOYLAN.
